UNITED STATES PATENT OFFICE.

JOHN D. BAILLIE, OF MOGADORE, OHIO, ASSIGNOR OF ONE-HALF TO JOHN R. MUSSON, OF SAME PLACE.

LIFTING-JACK.

SPECIFICATION forming part of Letters Patent No. 310,973, dated January 20, 1885.

Application filed October 6, 1884. (No model.)

To all whom it may concern:

Be it known that I, JOHN D. BAILLIE, of Mogadore, in Portage county, and State of Ohio, have invented a certain Improved Lifting-Jack, which may be employed in raising and lifting loads, carriages, railway-rails, ties, fences, logs, &c., of which the following is a specification.

The nature of said invention consists of a tubular standard attached to a base for supporting it. In the standard is a movable shaft connected at the upper end with a holding-brace, to which is pivoted a lever. This lever is also jointed to connecting rods or links, which are hinged at the lower ends to an adjustable yoke or collar on the standard. There is also an auxiliary attachment to the lifting-jack for the purpose of raising logs, blocks of stone, fences, and other bodies lying upon or in close relation to the ground.

For a more full and complete description of the said invention, reference will be had to the following specification, and to the annexed drawings, making part of the same, in which Figure 1 is a side view of the lifting-jack, lowered partially down. Fig. 2 represents it partially raised.

Like letters denote like parts in the drawings.

In the views, A represents the base, and B the tubular standard connected therewith. In said standard is a shaft, C, arranged to slide within it. To the top of the shaft is securely attached the holder or brace D, which is provided with an extension, D', and forming part of the holder D, for a purpose hereinafter described. The lever E is pivoted at a to the holder D, and on each side of the lever is jointed at b a link, F, Fig. 1. The lower ends of these links are hinged at c to the stem of the adjustable supporting-collar G, which collar is provided with a thumb or set screw, H, or the equivalent thereof. This collar G is adjustable on the tubular standard B, which

admits of its being raised or lowered, and secured in position by means of the thumb-screw. By lowering the collar G to the line d, Fig. 1, the support D will then rest upon the top of the standard. On turning the lever down to the position seen in Fig. 2 the support D is

raised from the position seen in Fig. 1 to that in Fig. 2. This arrangement of the said parts admits of the support being raised and lowered to various heights, as the nature and position of the load to be raised may need. The location of the collar G on the tubular standard determines the height, more or less, to which the support D may be raised, as circumstances may require. In case the thing or load to be raised is above the reach of the support D, then the section D' is employed, and the load being upon this section the raising of it is then done in the same way as when upon the support D.

By the adjustability of the double supports the lifting-jack may readily be adapted to various heights of carriage-axes and other things required to be raised without changing the position of the collar on the standard. In some cases it may be necessary to adjust the collar G in relation with the support D', to obtain sufficient height for the purpose desired.

It is often required to raise sections of farm and other fences and posts to be in line or otherwise. For this purpose I attach an auxiliary link to the supports D or D', (indicated by the dotted lines in Fig. 2.) The lower end of this removable link is provided with a hook, to be entered under the object to be raised by the same action, as before described. When the load or thing is raised and the lever moved down, as seen in Fig. 2, the joint b is then inside of the joint a, which locks or holds the jack in the raised position indicated in Fig. 2, and the load, being upon the supports D or D', will tend to force the joint b nearer the standard C, but is arrested from contact with it by the shoulders e, Fig. 2, of the lever bearing on the under side of the support D. The gravity of the load on the supports prevents the joint b from moving outside of the line of joints a c, thus locking the jack by the load upon it. The unlocking or lowering of the load is readily done by raising the lever.

This lifting-jack is preferably made of iron or steel, though certain parts may be of wood, and the links F F may be in one piece.

I am aware that a tubular standard with a movable standard therein, operated by means of levers, has been known and used, which I

do not claim *per se*; but what distinguishes my invention is the construction and arrangement herein shown and described.

I claim—

- 5 A lifting-jack consisting of a tubular standard having therein a movable lifting-shaft, the upper end of which terminates in an angular supporting brace or arm, to which is pivoted the minor end of a lever having its fulcrum in
10 the upper ends of a vibratory pair of links, between which the lever is pivoted, and the lower ends of the links pivoted to a yoke or collar adjustably attached to the tubular standard by a

set-screw, for the purpose of raising and lowering the shaft in the standard to adjust the implement to the object to be raised by means of the said lever as the major arm of which is forced downward, substantially as herein shown and described.

In testimony whereof I affix my signature in presence of two witnesses.

JOHN D. BAILLIE.
